Window and door designs for stores and dwelling

2021

Dec. 721

Winstow Ames, of Nashua, N. H.
Letters Patent No. 721, Dated Aug. 28th 1855.

The schedule referred to in these Letters Patent and making part of the same.

To all persons to whom these presents shall come.

Be it known that I Winstow Ames of Nashua of the County of Hillsborough, and State of New Hampshire, have invented or produced a new and ornamental design for a stove, or fireplace, and I do hereby declare that the same is fully represented in the accompanying drawings of which.

Figure 1. denotes a front elevation, and

Figure 2. an end elevation,

Figure 3. is a vertical section of the front plate such being taken on the line a, b. of fig 1.

Figure 4. is a vertical section of the end plate taken on the line c, d. of Figure 2.

The base or hearth plate is shown at A. it being surrounded by a fillet and curved ash pit rising B. which supports an ornamental cover C.

The front plate E, has a circular recess within which is a rotary semicircular blower which extends from E. to N. (see figures 1. 2. & 3. and turning on a center pin or stud C; It is ornamented in relief as seen in the drawings, and revolves in the circular recess, which is bounded by the fillet D.D. The lower half or flange of the back of the recess is ornamented with Gothic or pointed arches on curved columns which are depressed, as seen in Figure 1. the recesses being flanked by scrolled leaves.

The blower when in its upper position, covers a semi circular opening f. into the stove such opening being seen in Figure 3.

In Figures 1. 2. and 3. similar letters refer to similar parts in each.

2

Des. 721

The cap plate is shown at R, in the form of an open work urn resting on clawed cornices.

On the end of the stove is a door as seen at Q in Figures 2, 3, & 4.

The lower plate A, is supported on four feet A. The ornamental character of which as well as that of the remainder of the stove, is shown in the drawings, and with sufficient clearness to enable an expert pattern maker to comprehend and construct the design thereof.

What I claim is the ornamental design as exhibited in the accompanying drawings or more particularly that of the front plate and the end plate, the hearth plate, the legs, the top plate, and the blower.

In testimony whereof, I have hereunto set my signature this twenty fourth day of

July, 1. J. 1855.
